D. FISHER

TUMBLER

Filed Oct. 28, 1925

INVENTOR
David Fisher,
By Walter, Brown & Critchlow, his Attorney

UNITED STATES PATENT OFFICE.

DAVID FISHER, OF PADEN CITY, WEST VIRGINIA, ASSIGNOR TO PADEN CITY GLASS MANUFACTURING COMPANY, OF PADEN CITY, WEST VIRGINIA, A CORPORATION OF WEST VIRGINIA.

DESIGN FOR A TUMBLER.

Application filed October 28, 1925. Serial No. 15,278. Term of patent 7 years.

To all whom it may concern:

Be it known that I, DAVID FISHER, a citizen of the United States, residing at Paden City, West Virginia, have invented a new, original, and ornamental Design for Tumbler, of which the following is a specification, reference being had to the accompanying drawings, forming a part thereof.

The drawing is a side elevation of a tumbler, showing my new design.

I claim:

The ornamental design for a tumbler as shown.

DAVID FISHER.
